UNITED STATES PATENT OFFICE.

ROBERT C. CARLSON, OF CHICAGO, ILLINOIS.

REINFORCING CORNERS FOR BOXES.

Application filed September 18, 1922. Serial No. 588,777.

To all whom it may concern:

Be it known that I, ROBERT C. CARLSON, a citizen of the United States, and resident of Chicago, in the county of Cook and State 5 of Illinois, have invented a certain new and useful Improvement in Reinforcing Corners for Boxes, of which the following is a full, clear, concise, and exact description, reference being had to the accompanying 10 drawings, forming a part of this specification.

This invention relates to reinforcing corners for boxes. Boxes or cartons made of corrugated board or other forms of fibre are 15 ordinarily made of one piece of board which is scored and folded, certain edges being brought together and secured to one another to complete the enclosure. The meeting edges are frequently united by means of 20 fabric glued to the surface of the board and overlapping the joint between the edges. Boxes thus constructed are weakest at the corners, there being a tendency for the corrugated board or fibre to tear along the 25 scores and folds and along the united edges of the material. My invention relates to a reinforcing fabric having a U-shaped slot cut in it in a direction bias to the fabric threads, the fabric being preferably 30 gummed on one side for ready application to the box corners. The invention also embraces a fibre box having reinforcing corners of the type described applied thereto. My invention is illustrated in the accompanying drawing, in which—

Figure 1 is an isometrical drawing of a fibre box having all of its corners protected with bias reinforcing fabric;

Figure 2 illustrates the application of 40 the fabric to a box cover corner; and

Figure 3 illustrates the fabric as it is ordinarily applied to the fibre before the latter is shaped into a container.

The reinforcing fabric shown at 4 is provided with a slot 5 cut on the bias to the threads generally illustrated by the diagonal cross lines. The reinforcing member is preferably cut round, though this feature relates only to the appearance and it is obvious that other shapes may be used without affecting the utility of the invention.

Although it is obvious that the reinforcing members may be applied to the boxes in various ways, I have found it preferable to 55 apply gum to one side of the reinforcing fabric so that it may be attached to the box

merely by wetting. It is to be understood that the reinforcements may be applied either after the box has been completely formed or may be applied by the manufacturer who ordinarily sells the box in knock-down or flat condition.

Although I have described the reinforcing members as being made of material cut on the bias, it is also possible to construct these reinforcing devices of material which has no distinct weave, but which resists tear in at least one direction. When material of this kind is used, the U-shaped cut is made in the material in the same general 70 direction as that in which the material resists tear.

Although I have shown and described my invention as applied to boxes, it is to be understood that it may be applied to any form 75 of device having folds or corners which are improved by reinforcing.

1 claim:

1. In combination with a box having a rectangular corner formed by side walls and superposed flaps, a corner reinforcing member of textile fabric having an open ended slot and adhering to the side walls and flaps, those portions of the reinforcing member adjacent the open end of said slot adhering 80 to the flaps and lying in superposed relation, said reinforcing member being folded over the side wall junction and the junctions between the side walls and flaps along lines substantially at 45° to both the warp and 85 the weft of the fabric, whereby said warp and weft strands substantially equally resist disruption of the reinforcing member along the lines of the folds.

2. In combination with a box having a 95 rectangular corner formed by side walls and flaps, a slotted reinforcing member of textile fabric adhering to the side walls and flaps and being folded over the side wall junctions and the junctions between the side 100 walls and flaps with both the warp and weft strands of the fabric so disposed with respect to the lines of the folds that such strands substantially equally resist tearing along the folds.

3. The combination with a corner of a box formed from a sheet folded along two lines at right angles, said sheet being cut along one of said folds outwardly from the intersection of said folds, the two quarters thus 105 formed adjacent said cut being folded into mutually superimposed relation when the

2
box is completely formed, of a fabric re-enforcing member adhering to said corner, said reenforcing member having a slot cut from substantially the intersection of said folds, said slot extending at such an angle to the weave of said fabric that tearing strains along said folds are borne substantially equally by the warp and weft of said fabric, one lateral edge of said slot extend-

ing to the superimposed lateral edge of the 10 cut in said sheet for protecting and reenforcing the latter edge.

In witness whereof, I hereunto subscribe my name this 13th day of September, 1922.

ROBERT C. CARLSON.

Witnesses:

EDNA V. GUSTAFSON,
DAGMAR PETERSON.
